(57) **CLAIM**

The ornamental design for a network diagnostic device, as
shown and described.

DESCRIPTION

FIG. 1 is a front/left-side/bottom perspective view of the
network diagnostic device comprising the present invention;
FIG. 2 is a front/right-side/top perspective view thereof;
FIG. 3 is a rear/right-side/top perspective view thereof;
FIG. 4 is a front view thereof;
FIG. 5 is a rear view thereof;
FIG. 6 is a top view thereof;
FIG. 7 is a bottom view thereof;
FIG. 8 is a side view thereof; and,
FIG. 9 is another side view thereof.
Broken lines are shown for illustrative purposes only and
form no part of the claimed design.
